UNITED STATES PATENT OFFICE.

SANTOS AMSELEM, OF NEW YORK, N. Y.

DESIGN FOR A FANCY TOY BALL.

SPECIFICATION forming part of Design No. 21,060, dated September 22, 1891.

Application filed May 6, 1891. Serial No. 391,822. Term of patent 7 years.

To all whom it may concern:

Be it known that I, SANTOS AMSELEM, a citizen of the United States, residing in the city, county, and State of New York, have invented and produced a new and original Design for 5 Fancy Toy Balls, of which the following is a specification.

Reference is to be had to the accompanying drawing, forming a part of this specification, 10 in which the figure is a side elevation of the design.

The leading feature of the design consists in the representation of a sphere A, having

an ornamental surface partly covered by raised meridian-cords B. The ornamentation 15 of the ball consists of a broad encircling band formed with ornamental lines giving a wavy appearance.

I claim—

The design for fancy toy balls herein shown and described.

SANTOS AMSELEM.
